UNITED STATES PATENT OFFICE.

THEODOR KUNDTZ, OF CLEVELAND, OHIO.

DESIGN FOR A SEWING - MACHINE COVER.

SPECIFICATION forming part of Design No. 19,200, dated July 9, 1889.

Application filed May 28, 1889. Serial No. 312,462. Term of patent 7 years.

To all whom it may concern:

Be it known that I, THEODOR KUNDTZ, a citizen of the United States, residing at Cleveland, in the county of Cuyahoga and State of Ohio, have invented and produced a new and original Design for a Sewing-Machine Cover, of which the following is a specification, reference being had to the accompanying drawing, forming a part thereof.

10 The figure is a view in perspective.

The sides A A of the cover have upper rounded corners. The cap has the appearance of a raised panel, which, together with the adjacent rounded corner, produces a pleasing effect. A molding D is below the rounded corner aforesaid. The molding consists of a concaved section d and a reverse beaded slope d', substantially as shown. The mold-

ing above the edge d² thereof stands out some little distance from the face of member A, 20 and gives a bold, striking appearance. At the base of the cover is located molding E, the same having a recess e.

What I claim is—

A design for a sewing-machine cover, comprising the sides, a raised panel at its top, molding below the raised panel, and recessed molding along the bottom edge of the cover, substantially as set forth.

In testimony whereof I sign this specification, in the presence of two witnesses, this 23d day of March, 1889.

THEODOR KUNDTZ.
